(57) **CLAIM**

I claim the ornamental design for a adjustable bed, as shown and described.

DESCRIPTION

FIG. 1 is a perspective view of a adjustable bed design in a first position; and,

FIG. 2 is a side perspective view of the design of FIG. 1 in the first position.

The broken lines are for environmental purposes only and form no part of the claimed design.

1 Claim, 1 Drawing Sheet

FIG. 1

FIG. 2
